UNITED STATES PATENT OFFICE.

WILLIAM WEISSAGER, OF JERSEY CITY, NEW JERSEY.

COMBINED YARD-STICK AND SQUARE.

SPECIFICATION forming part of Letters Patent No. 416,024, dated November 26, 1889.

Application filed July 13, 1889. Serial No. 317,419. (No model.)

To all whom it may concern:

Be it known that I, WILLIAM WEISSAGER, a citizen of the United States, and a resident of Jersey City, in the county of Hudson and 5 State of New Jersey, have invented certain new and useful Improvements in Combined Yard-Stick and Square, of which the following is a specification.

My invention relates to a new and useful 10 combined yard-stick and square; and it consists in the construction of the device hereinafter set forth.

In the drawings the same reference-letters indicate the same parts in all the figures.

15 Figure 1 illustrates a side view of the device, all parts being in position when it is used as a yard-stick. Fig. 2 illustrates a side view of the device, all parts being in position when it is used as a square. Figs. 3, 4, 5, 6, 20 and 7 are side views of the device partly broken away, showing the several movements and the positions of the parts when it is being converted from a yard-stick to a square.

A is one section of the device, and B is the 25 other, which is adapted to be moved and held in line with or at right angles to the part A, as hereinafter set forth. These parts A and B may be made of metal or of wood, or of wood and metal, as preferred. It is better 30 that the ends of both of the parts adjacent to the joint should be of metal, in order that the joint may be strong and the engagement of the parts more accurate, thus securing a good and stiff right-angle connection.

35 For use by tailors and other similar uses, the main part of the device may be made of wood, but for masons' and carpenters' use it should preferably be made entirely of metal.

The parts constituting the joint are as fol- 40 lows:

D is a plate projecting from the part B, and located centrally between the two side pieces or plates E and F of the part A.

G is a slot made in the plate D, as shown.

45 H is a pin which passes through the two side plates E and F of the part A and plays in the slot G.

I is a locking-plate, which slides in a suitable undercut or dovetail slideway I', made 50 in the face of the metal plate forming the end of the piece B, as shown, and J and K are

two recesses, also undercut or dovetailed, placed at right angles to each other and made in the outer plate E of the part A, into which the end of the locking-plate I may enter with 55 a snug fit.

L is a thumb-crease in the sliding locking-plate I, whereby it may be easily moved by the thumb-nail or other suitable means.

The operation is as follows: To put the de- 60 vice in extended position for use as a yard-stick, as shown in Fig. 1, the pin is caused to move through the inclined part a of the slot G, and when the parts A and B are snugly pushed together, abutting against each other, 65 the pin will be in the upper part of the said slot, as shown in Figs. 1 and 3, and the locking-plate I may then be pushed into the recess J, whereby the parts will be locked firmly together, owing to the inclination of the part a 70 of the slot acting upon the lock-plate through the pin H in such manner as to give it the action of a key, which firmly holds the parts together.

To alter the position of the parts so that 75 they shall be at right angles to each other for use as a square, as shown in Figs. 6 and 7, the locking-plate I is shoved back and the parts are manipulated so that the pin passes through the part of the slot marked a until it 80 reaches the part marked b, as shown in Fig. 4. The end marked B may then be swung around, as indicated by the arrow in Figs. 3 and 4, it having been separated from the part A sufficiently to clear the corners there- 85 of (marked c) from contact with the shoulders d of the part marked A. The swinging of the part B being continued in the direction of the arrow, the pin is caused to pass through the part marked e of the slot G, as shown in 90 Fig. 5, and finally it is passed into the bayonet-joint locking part f of the slot, as shown in Fig. 7, having passed through the part marked g of the slot, and when in this position the parts will be firmly together at right 95 angles to each other. The locking-plate I is then again pushed forward, its end entering the recess K in the plate E, thus locking the parts firmly together.

Having described my invention, I claim— 100

A combined yard-stick and square comprising, essentially, two parts, a pin attached

to one part, a locking-plate attached to one of the parts, the part to which the locking-plate is not attached being provided with recesses, which have lateral presentation at right angles to each other, adapted to receive the end of the locking-plate, and the part to which the pin is not attached being provided with a slot, through which the pin may move during the adjustments of the parts, substantially as 5 and for the purposes set forth.

Signed at New York, in the county of New York and State of New York, this 12th day of July, A. D. 1889.

WILLIAM WEISSAGER.
